DRILL PRESS FOR TAPPING ATTACHMENT

Harry G. Procnier, Chicago, Ill.

Application January 23, 1939, Serial No. 252,349

5 Claims. (Cl. 10—139)

An object of this invention is to provide a drill press for tapping attachment which may be operable by a member which is positively driven in both directions but which drives through connections which are yieldable in either direction if the tap or other tool employed is stuck or forcibly held or is prevented from entering the work for any reason thereby preventing breakage of the tool or associated parts.

10 An other object is the provision of means for readily and separately adjusting the force exerted by the yieldable means for forcing the tap into the work and for withdrawing it therefrom.

15 Still another object is the simplification of these adjusting means and their location with respect to the work so that an operator can readily adjust the pressure to be applied to a shaft carrying the tapping attachment either in feeding or withdrawing the tap without moving from the position he normally occupies at the machine.

20 These and other objects as will hereinafter appear are accomplished by this invention which is fully described in the following specification and shown in the accompanying drawing in which:

25 Figure 1 is a perspective view of a drill press with tapping attachment embodying the invention;

30 Fig. 2 is an enlarged vertical section on the line 2—2 of Fig. 1; and

Fig. 3 is an enlarged transverse section on the line 3—3 of Fig. 2.

35 This is an improvement on my application for Drill press for tapping attachment, Serial No. 130,325, filed March 11, 1937, since issued as Patent No. 2,160,674, May 30, 1939.

The embodiment illustrated comprises a drill press having a base 10 from which rises a tubular standard 11 on which is mounted a bracket 12 which carries a motor 13 at one side while in the other side is suitably journaled a shaft 14, the shaft being driven by means of a stepped pulley 15 operably connected to the shaft while a stepped pulley 16 is keyed to the motor shaft, the stepped pulleys being operably connected by means of a belt 17 or the like.

40 The shaft 14 carries a tapping attachment 18 which in turn carries a chuck 19 for holding a tap 20. A table 21 is adjustably carried upon the standard and is adapted to hold the work to be tapped.

45 The apparatus heretofore described is well known to the art. The means for raising and

lowering the shaft 14 together with the tapping attachment 18 and tap 20 form the basis for the present invention and will now be described in detail. A slide 22 is slidably guided in guideways 23, 24 and carries an arm 25 which is operably secured to the shaft 14 so that the shaft and the slide move up and down together.

50 The slide 22 is hollow and internally threaded to receive the upper threaded end of a compression adjusting rod 26 which is adjustably screwed therein after which it is locked in place by means of a lock nut 27. The lower end of this compression rod is threaded and has an adjusting nut 28 screwed thereon. This nut carries a screw 29 which extends outwardly from the nut and serves for rotating the same with respect to the rod 26 as will presently be explained.

55 Above the nut 28 and serving as an upper stop therefor is a collar 30 which is secured thereto as by means of a tapered pin 31. An upper adjusting sleeve 32 surrounds the collar and nut as well as the lower end of the compression rod and is secured at its upper end to a ring 33 which is slidably fitted over the compression rod. The upper end of the sleeve is riveted over the ring. This sleeve has a vertically extending slot 34 which serves as a guide for the screw 29.

60 At the lower end of the rod 26 is an intermediate sleeve 35 having an enlarged unrolled portion 36 with upper and lower reduced cylindrical portions. On the upper cylindrical portion is rotatably mounted a ferrule 37, the upper end of which is reduced and screw-threaded to receive the lower screw-threaded end of the sleeve 32. The outer surfaces of the sleeve and the 65 enlarged portion of the ferrule 37 are preferably of the same diameter. This ferrule is placed over the reduced upper end of the sleeve 35 after which a retaining ring 38 is placed thereover and the two riveted or otherwise secured in place with sufficient looseness, however, to permit the ferrule to be readily rotated on the intermediate sleeve. Upon assembling, however, the ferrule is held while the sleeve 32 is firmly secured in place thereon after which the two normally rotate together to effect the rotation of the nut 28 on the compression adjusting rod 26.

70 The lower end of the intermediate sleeve 35 is a duplicate of that described and has rotatably mounted thereon a ferrule 39 which is retained in place by means of a ring 40. The ferrule 39 is similarly reduced and screw-threaded to receive the upper screw-threaded end of a lower adjusting sleeve 41. The lower end of this sleeve has a ring 42 secured therein as by riveting and this 75

ring is rotatable on a tension adjusting rod 43 which has a collar 44 secured thereon by means of a tapered pin 45. This collar acts as the lower limit for the sleeve 41 and the collar 44 acts to transmit an upward thrust of the rod 43 to the sleeves above as will soon be apparent. The lower end of the rod 43 is screw-threaded to be screwed into the upper end of a power rod 46 and is locked thereto by means of a nut 47. 5 This power rod may be a piston rod operating in an air cylinder 48 and may be driven up and down by means of air fed to the cylinder through pipes 49. The mechanism for operating such a power mechanism is quite complicated particularly where it is set to drive the rod 46 up and down at a predetermined rate which may be adjusted. This mechanism, however, forms no part of the present invention and therefore is not shown in detail. 10

20 The tension adjusting rod 43 likewise carries a nut 50 which has an adjusting screw 51 which extends through a slot 52 in the lower adjusting sleeve 41. A compression spring 53 is placed between the nut 50 and the ring 42. Likewise, a compression spring 54 constantly exerts pressure between the nut 23 and the ring 38 within the upper adjusting sleeve. 15

It will be apparent from the foregoing that as the power rod 46 is lowered, pressure is exerted through the nut 50 upon the compression spring 53 thereby placing the sleeves 41, 35 and 32 in tension. The sleeve 32 is firmly secured to the ring 33 and this bears directly upon the collar 30, thence through the rod 26, through the slide 35 20 and arm 25 to the shaft 14 and ultimately to the tap 20. It will be observed that in this operation the only yieldable member is the compression spring 53 and that the stiffness of this spring will depend upon the setting of the nut 40 50. If, therefore, the tap in being lowered misses the hole, which it is intended to screw-thread, and instead strikes a solid portion of the work, the spring 53 will yield and no damage will be done. 45

In backing the tap out of the work, it sometimes happens that the tap will become clogged with chips and will stick in the work. When this occurs, pressure is exerted by the power rod upon the sleeves 35 and 41 thereby causing the rod 50 55 to be forced into the sleeve 32 compressing the spring 54. This again insures against any damage being done due to forcing the tap at a time when it is stuck in backing it out.

The adjusting sleeves are so placed as to be readily accessible to an operator who either stands or sits in front of the tapping machine. With a little practice he will readily understand that a little more pressure or a little less is required to properly drive the tap into the work and he can accordingly adjust the sleeve 41 to give the necessary pressure. Also he will soon learn just how much adjustment is required of the upper adjusting sleeve 32 to give the best result in backing the tap out of the work. In either of these adjusting operations it is usually sufficient for him to take hold of the necessary adjusting sleeve and to turn it without holding the other sleeve. However, should it be desirable to hold the other sleeve, this can readily be done 60 65

by hand or by adding a bracket to the intermediate sleeve enlargement 36 which bracket will engage any stationary part of the drill press such as the standard 11. 5

Thus it will be seen that a very simplified and efficient form of drill press is provided with particular application to its use with tapping attachments. While I have shown and described but a single embodiment of my invention, it is to be understood that it is capable of many modifications. Changes, therefore, in the construction and arrangement may be made which do not depart from the spirit and scope of the invention as disclosed in the appended claims. 10

I claim: 15

1. In a tapping machine, a shaft, means for rotating the shaft, an operating rod movable up and down, means operably connecting said rod and the shaft for raising and lowering the shaft including two springs, one of which is yieldable 20 as the rod is raised and the other is yieldable as the rod is lowered, and a sleeve enclosing each of the springs, both sleeves being individually adjustable by an operator from his normal position while operating the machine. 25

2. In a tapping machine, a shaft, means for rotating the shaft, an operating rod movable up and down, means operably connecting said rod and the shaft for raising and lowering the shaft including two springs, one of which is yieldable as 30 the rod is raised and the other is yieldable as the rod is lowered, and a sleeve enclosing each of the springs, the rod and the two springs being in alignment, both sleeves being individually adjustable by an operator from his normal position 35 while operating the machine.

3. In a tapping machine, a shaft, means for rotating the shaft, an operating rod movable up and down, means operably connecting said rod and the shaft for raising and lowering the shaft 40 including two springs, one of which is yieldable as the rod is raised and the other is yieldable as the rod is lowered, a sleeve enclosing each of the springs, and means operable by each sleeve for adjusting the stress in its spring. 45

4. In a tapping machine, a shaft, means for rotating the shaft, an operating rod movable up and down, means operably connecting said rod and the shaft for raising and lowering the shaft including two springs, one of which is yieldable 50 as the rod is raised and the other is yieldable as the rod is lowered, a sleeve enclosing each of the springs, and means operable by each sleeve for adjusting the stress in its spring, the two sleeves being in axial alignment. 55

5. In a tapping machine, a shaft, means for rotating the shaft, an operating rod movable up and down, means operably connecting said rod and the shaft for raising and lowering the shaft including two springs, one of which is yieldable 60 as the rod is raised and the other is yieldable as the rod is lowered, a sleeve enclosing each of the springs, and means operable by each sleeve for adjusting the stress in its spring, the two sleeves being in axial alignment and being connected so 65 that either can be rotated with respect to the other to individually adjust either spring.

HARRY G. PROCUNIER.
